(57) **CLAIM**

The ornamental design for an electric driver drill, as shown and described.

DESCRIPTION

FIG. 1 is a perspective view of an electric driver drill;
FIG. 2 is a left side elevational view thereof;
FIG. 3 is a right side elevational view thereof;
FIG. 4 is a front elevational view thereof;
FIG. 5 is a rear elevational view thereof;
FIG. 6 is a top plan view thereof; and,
FIG. 7 is a bottom plan view of the present invention.
No claim is made to the portions of the electric driver drill
illustrated in phantom outline.
